FREDERICK F. McMAHON, OF BRIDGEPORT, CONNECTICUT.

DEVICE FOR HANGING CURTAINS.

1,408,755.

Specification of Letters Patent.

Patented Mar. 7, 1922.

Application filed January 21, 1921. Serial No. 438,877.

To all whom it may concern:

Be it known that I, FREDERICK F. McMAHON, a citizen of the United States, residing at 1801 East Main Street, Bridgeport, county of Fairfield, State of Connecticut, have invented an Improvement in Devices for Hanging Curtains, of which the following is a specification.

This invention relates to a novel device 10 for hanging curtains, referring more particularly to a device especially adapted for use in alining the lower edges of curtains at the time of hanging, and the primary object thereof is to provide a simple and efficient device comprising a standard mounted on a base which holds the standard in upright position when placed on the floor, and an adjustable cross bar having means for fastening the curtains thereto. The device 20 provided by my invention is inexpensive to manufacture, and one which may be taken apart and placed together in a compact unit, when not in use.

A further object of the invention is to 25 provide a scale on the standard of my improved device, adapted to cooperate with an edge of the cross bar for determining the height of the lower edge of the curtains from the floor, the same being extremely useful when it is desired to hang a number of 30 curtains with their lower edges at the same distance from the floor, it being apparent that my device may be used both as a gage for determining the height from the floor 35 and for correctly alining curtains.

With the above and other objects in view, I have devised the novel device for hanging curtains which I will now describe, referring to the accompanying drawing forming 40 a part of this specification and using reference characters to indicate the several parts.

Fig. 1 is a side elevation of my novel device for hanging curtains as in use;

Fig. 2, a sectional view, on an enlarged 45 scale, on the line 2—2 in Fig. 4;

Fig. 3, a plan view of the novel device;

Fig. 4, a front elevation thereof; and

Fig. 5 is a fragmentary view of the opposite side of the standard and cross bar illustrated in Fig. 4, showing a scale on the 50 standard.

10 denotes a base, 11 a standard secured to the base by a hinge 12, or other suitable means, and 13 a cross bar adjustable on the 55 standard. Means, as a hook 14, is provided for the purpose of locking the standard in

an upright position, the hook being attached to the base and adapted to engage an eye 15 screwed into the standard. The standard may be folded down on the base and the 60 cross bar removed, when the device is not in use, thus providing a compact unit which is easily stored. The cross bar is provided with a plurality of projecting pins 16, fixed therein in any desired manner, which are 65 adapted to attach curtains 17 to the cross bar for the purpose to be described.

The cross bar is recessed at 18, preferably in the central portion so that the ends will balance, to receive the standard, the cross 70 bar being slidable longitudinally thereon. The cross bar is shown as adjustably secured to the standard by means of a plate 19 secured to the cross piece over recess 18 and having integral with it, or attached 75 thereto, a spring 20 which bears against the bottom of a groove 21 formed in the standard. A convenient and practicable way of forming the spring is to, as illustrated in the drawing, make the plate 19 with a narrow 80 tongue projecting centrally therefrom, and to bend said tongue so that it will lie adjacent the back of the plate, the bend affording sufficient resiliency to keep the end of the tongue sprung outwardly from the plate. 85 The friction of the spring alone, on the bottom of groove 21, may be used to hold the cross bar in adjusted position, or a thumb screw 22, threaded in the plate and bearing on the spring, may be utilized to 90 lock the cross bar in any desired position.

As shown in Fig. 5, a scale 23 may be provided on the standard, the lower edge of the cross bar registering with the scale to indicate the height of the cross bar from 95 the floor.

The various parts of my novel device may be inexpensively constructed of wood or pressed metal, and are simple and durable. In use the device is placed with the base on 100 the floor underneath a curtain pole 24, upon which curtains 17 are to be hung, the cross bar being positioned parallel with the pole and at the desired distance from the floor. The upper end of the curtain is passed 105 loosely over the pole and the lower end thereof is attached to the pins 16 on the cross bar. The upper end of the curtain is then secured to the pole in any suitable manner.

I thus provide a simple device for hanging curtains, which is easily operated by one

person, and which will aline the bottom edges without tentative adjustment, thus eliminating the heretofore tedious work of curtain hanging, which has often required 5 climbing up and down a step-ladder several times in order to get the sides and centers of the lower ends of curtains in alinement. It will also be seen that with the novel device provided herein, it is possible to aline 10 two or more curtains at the same time. My device is extremely useful where it is desired to hang curtains, located at different windows about a room, with their lower edges at the same height from the floor, the cross 15 bar being first fixed at the required height and used as a gage thereafter.

It is to be understood that the embodiment 20 of the invention disclosed herein is illustrative and not restrictive and that the invention contemplates such modifications in construction and arrangement of parts as may be made within the spirit and scope of the following claims:

1. A device of the character described 25 comprising a base, a hinged standard, a cross bar having a recess to receive the standard, a plate over the recess, and means on the plate for adjustably securing the cross bar on the standard.

30 2. A device of the character described

comprising a base, a standard hinged thereto, means for securing the standard in upright position, a cross bar adjustable on the standard, and means for locking the cross bar to the standard.

35

3. A device of the character described comprising a base, a standard, a cross bar having a recess adapted to receive the standard, a plate on the cross bar bridging said recess and retaining the cross bar on the 40 standard, and means on the cross bar for attaching curtains thereto.

4. A device of the character described comprising a base, a standard, an adjustable cross bar having a recess adapted to receive 45 the standard, a plate bridging said recess, a spring carried by the plate and engaging the standard, and a screw carried by the plate and bearing against the spring.

5. A device of the character described 50 comprising a base, a standard provided with a longitudinal groove, a cross bar having a recess adapted to receive the standard, a plate bridging said recess and retaining the cross bar on the standard, a spring carried 55 by the plate and bearing against the bottom of the groove, and a thumb screw passing through the plate and engaging the spring.

In testimony whereof I affix my signature.

FREDERICK F. McMAHON.
